DESIGN FOR A WRENCH

Amos F. Lewis, St. Louis, Mo.

Application December 20, 1945, Serial No. 124,902

Term of patent 7 years

(Cl. D54—16)

To all whom it may concern:

Be it known that I, Amos F. Lewis, a citizen of the United States, residing in the city of St. Louis, State of Missouri, have invented a new, original, and ornamental Design for a Wrench, of which the following is a specification, reference being had to the accompanying drawing, forming a part thereof.

In the drawing:

Figure 1 is a plan view of a wrench, showing my new design;

Figure 2 is a side view thereof;

Figure 3 is an end view of the head of the said wrench;

Figure 4 is a sectional view of the shank, taken at line 4—4 of Figure 1; and,

Figure 5 is an end view of the shank.

I claim:

The ornamental design for a wrench, substantially as shown.

AMOS F. LEWIS.
